UNITED STATES PATENT OFFICE.

HOWARD M. SHERWOOD, OF PHOENIX, NEW YORK, ASSIGNOR OF ONE-HALF TO
MICHAEL C. RYAN, OF PHOENIX, NEW YORK.

CONCRETE-FORM FASTENER.

1,069,821.

Specification of Letters Patent. Patented Aug. 12, 1913.

Application filed March 11, 1908. Serial No. 420,433.

To all whom it may concern:

Be it known that I, HOWARD M. SHERWOOD, a citizen of the United States, residing at Phoenix, Oswego county, New York, have invented certain new and useful Improvements in Concrete-Form Fasteners; and I do hereby declare the following to be a full, clear, and exact description of the invention, such as will enable others skilled 10 in the art to which it appertains to make and use the same.

This invention relates to certain improvements in devices employed in connection with the construction of concrete walls and the like, and more particularly relates to an improved concrete form fastener; and the objects and nature of my invention will be readily understood by those skilled in the art in the light of the following explanation 20 of the structure illustrated by the accompanying drawings as my preferred embodiment from among other formations within the spirit and scope of my invention.

Referring to the accompanying drawings:—Figure 1, is a vertical section through a concrete form fastened by devices of my invention, showing a portion of the concrete wall or other body therein. Fig. 2, is a horizontal section through a body of concrete, 30 showing the form walls, and fasteners therein, one of the bolts or screws of the upper fastener is shown partially withdrawn, while the bolts of the lower fastener have been entirely withdrawn. Fig. 3, is a perspective view showing the parts of a tie or fastener detached from each other. Fig. 4, is a vertical section through form walls and an intervening body of concrete showing the opposite bolts or screws arranged out of line 35 or in different planes and the fastener or tie bent or adjusted to receive both bolts. Fig. 5, shows a modified form.

In building up forms for the construction of concrete walls, it is a common practice 45 to employ wire for the purpose of holding up the sides or walls of the wooden form. Spacing blocks are usually placed between the opposite plank walls of the form and then lengths of wire are passed across the 50 space between the form sides and through the planking thereof and secured or twisted around the frame beams or girders at the outer faces of the planking. The wire stretches and it is necessary to twist the 55 same to hold the walls up against said blocks

and spaced the desired distance apart to form a concrete wall of the desired thickness between said wood form walls.

The process of securing the form walls by wire is comparatively slow and expensive and usually it is with difficulty that the form walls are properly held and maintained by the wires during the process of filling in the space between said walls with concrete. After the completion of the concrete work between the form walls, the wire ties render the work of removing the form walls somewhat difficult. The lengths of tie wire passing across the space between the form walls are embedded in the concrete 65 and in actual practice it is difficult to break or cut the wire without marring the concrete work or leaving objectionable projecting wire lengths.

It is an object of my invention to provide 75 fastening means for the form walls which can be produced at a low cost and which can be readily applied and easily adjusted to hold the forms to proper position and when so applied will not stretch and which 80 will permit rapid and easy removal of the form sides after completion of the concrete wall without marring or damaging the concrete work.

A further object of my invention is to 85 provide fastening or tie means for whatever purpose to which the same may be adapted and which can be produced at a low cost, and can be readily and easily applied to 90 walls or the like, to hold them to proper position, and which if so desired, can be readily removed in part.

In the example illustrated by the accompanying drawings, a wall tie or fastening is shown comprising a connecting link or 95 body length 2, usually of sheet metal such as band iron or steel; two end stirrups or loops 3, at their ends secured as by rivets 4, to the ends of the link or body 2; nuts 5, arranged within the loops or stirrups 3; and screws or suitable bolts 6, adapted to pass through the form walls, perforations 100 in the stirrups, and into the nuts confined within the stirrups.

In the drawings, for the purpose of illustrating an application of my invention, I show a convenient construction and arrangement of wood form which can be employed to constitute the form or mold in which the concrete wall or other body is built up, 110

molded and confined and wherein the body of concrete is allowed to set until sufficiently hard to permit removal of the wood work constituting the mold or form. However, I do not wish to limit my invention to use in connection with any particular construction or arrangement of form, structure or other construction work.

The wood form shown comprises the opposite plank walls 8, forming the space in which the concrete is deposited and tamped, and vertical and horizontal beams or girders 9, 10, arranged at the outer side of the planking 8, and forming the supporting and strengthening backing and frame therefor.

In practice, each end stirrup 3, is usually bent up from band or strap metal to form the flat outer end having the perforation 7, and constituting the nut receiving seat, and the inwardly extending legs which have their ends perforated and engaging opposite faces of an end of the body length 2, also perforated to receive the rivet 4, securing the stirrup ends to the body length so that the stirrup forms an encircling open loop to loosely receive a nut. The two stirrups virtually form extensions or continuations of the body length 2, projecting beyond the opposite ends thereof.

The fastener comprising the body length and stirrups is in length less than the width of the mold, that is than the thickness of the concrete wall or other body formed therein. Usually the flat outer ends are arranged say about an inch, more or less, from the adjacent inner faces of the form walls.

As the distances between different form walls vary according to the thickness of the concrete bodies to be built, the body lengths 2, can be cut of different sizes to produce fasteners of the length desired for any particular wall, so that bolts of practically the same length can be employed on approximately all work and the stirrup ends will be spaced the desired distances from the inner surfaces of the form walls.

As the form walls are built up, the fastening devices can be applied at the desired points and spaced the desired distance apart to hold the walls up in the required positions. Each fastener forms the connection between a pair of bolts passed in opposite directions inwardly and removably through the opposite form walls, and screwed into the nuts confined or resting loosely in the stirrups. The bolts can be turned by their headed outer ends to draw the form walls tightly up to form the concrete receiving space of the desired width. The concrete is then packed in the space between the form walls so that the fasteners are completely inclosed and embedded therein with the concrete passing through the stirrups and around the nuts. If the holes for the bolts

in the form sides should not be in alinement, that is if the opposite bolts are out of line, as shown for instance in Fig. 4, the tie can be bent or adjusted on the rivets or pins 4, so that the bolt ends can enter their respective nuts, and the link 2, will extend at an angle or inclination between the end stirrups. When the concrete has set to the desired extent in order to permit removal of the form walls, it is only necessary to unscrew the bolts from the nuts and withdraw the same outwardly from the form walls. The form walls can be then quickly and easily removed from the concrete wall, leaving the fasteners embedded therein and acting as metal reinforcing elements for the concrete. When the bolts are withdrawn they leave small holes extending through the concrete to the stirrup ends, which holes, if so desired, can be easily and quickly filled or pointed up.

These fasteners can be produced economically and used in connection with standard or stock nuts and bolts, and a material saving in cost of concrete work is effected by the use of my invention notwithstanding the fact that the fasteners and nuts remain in the concrete walls.

In Fig. 5, I show the body length 20, and the end stirrups 30, bent from a single length of bar or band iron or steel or other suitable metal; rivets 40, being provided to secure the free ends of the metal to the intermediate or body portion.

It is evident that various changes and modifications might be resorted to without departing from the spirit and scope of my invention and hence I do not wish to limit myself to the exact construction disclosed.

What I claim is:—

1. Means adapted to form a securing connection between temporary concrete-form walls, consisting in the combination of a pair of removable bolts adapted to extend inwardly through and secure opposite form walls, a pair of nuts for the inner ends of said bolts, and a connecting body length between said bolt ends and at its ends provided with concrete-receiving and nut-encircling and seat forming loops in longitudinal continuation of the body length and perforated for passage of said bolt ends to said nuts, said body length and its loops and the nuts adapted to remain embedded in the concrete structure, and said bolts adapted to be removed from the form walls, the nuts and the concrete.

2. A concrete form fastener consisting essentially of a pair of nuts, a pair of form wall holding headed bolts adapted to said nuts, a pair of laterally enlarged encircling nut-seat-forming and concrete-receiving riveted loops and a single straight connecting body length between and joining said loops, said loops formed to receive, and hold said

nuts and perforated for the free passage of said bolts to and from said nuts.

3. A concrete form fastener consisting of a pair of nuts, a pair of removable concrete form wall securing bolts, and a pair of nut-receiving- and holding loops and a connecting body length between the loops, each loop being swingably joined to said body length and having diverging side walls in 10 outward continuation of the body length

and connected by a transverse nut-seat forming outer end wall adapted for the free passage of a bolt to and from a nut in the loop and resting against said end wall.

In testimony whereof I affix my signature, 15 in presence of two witnesses.

HOWARD M. SHERWOOD.
